UNITED STATES PATENT OFFICE

BURTON W. KENDALL, OF EAST ORANGE, NEW JERSEY, ASSIGNOR TO WESTERN ELECTRIC COMPANY, INCORPORATED, OF NEW YORK, N. Y., A CORPORATION OF NEW YORK

HIGH FREQUENCY SIGNALING

Original application filed November 9, 1916, Serial No. 130,350. Patent No. 1,773,901, dated August 26, 1930.
Divided and this application filed October 26, 1928. Serial No. 315,121.

This is a division of my application Serial No. 130,350, filed November 9, 1916, patented August 26, 1930, No. 1,773,901, for high frequency signaling.

This invention relates to high frequency signaling, in which signals are transmitted as modulations of a high frequency wave.

In United States Patent 1,330,471 to B. W. Kendall, patented February 10, 1920, for high frequency signaling, it is shown how the homodyne method of reception is adapted to telephonic signaling. According to this method, the detected signal is intensified by combining the received modulated oscillations with locally generated oscillations of a frequency the same as the carrier frequency. The oscillations generated at the receiving station will hereafter be termed reinforcing oscillations for brevity and to differentiate them from the carrier oscillations generated at the sending station. If the carrier oscillations have a frequency which is not equal in value to the reinforcing frequency, beats are produced having a frequency equal to the difference in the frequencies of the carrier and the reinforcing oscillations. These beats are manifested as a sound or noise which is superimposed upon the signal being received, and this interferes with a clear and distinct reception of the signal.

To prevent a masking of the signal by such a sound or noise, the present invention has for an object to provide method and means for insuring that the carrier and reinforcing frequencies shall have identical values.

This is accomplished by generating control oscillations, and by changing the frequency thereof to provide a source of carrier oscillations which are modulated in accordance with a signal to be transmitted. The control oscillations and the modulated oscillations are sent to the receiving station where the frequency of the control oscillations is changed, in the same manner as it was at the sending station, to provide a source of reinforcing oscillations which are combined with the received modulated oscillations to reproduce the signal. Since there is a single source of control oscillations from which both the carrier and reinforcing oscillations are derived,

the carrier and reinforcing oscillations will always have the same frequency which may, however, assume different values, due to variations in the control frequency.

It is shown how this scheme of frequency control may be embodied in a multiplex system in which the frequency changing means at the sending station generates a plurality of frequencies which are multiples of each other, and corresponding reinforcing frequencies are generated at the receiving station.

The frequency changer used in the systems above described is a harmonic generator which gives only a relatively small number of frequencies within a given frequency range, since there are generated only those frequencies which are multiples of the frequency supplied to the harmonic generator.

Other objects of the invention are to make a larger number of frequencies available within a given frequency range than would be possible if only a single control frequency were used, and to provide frequencies which are not multiples of each other.

This is accomplished by generating two frequencies, for instance, oscillations of 3000 and 4000 cycles, which are individually supplied to harmonic generators, each of which gives any desired multiple of the frequency supplied to it. The third multiple, 9000, for example, from the 3000 cycle harmonic generator may be combined in a thermionic device with the fourth multiple, 16,000, supplied by the 4000 cycle harmonic generator to produce a frequency equal to their sum, 9000 plus 16,000, or 25,000, which is a frequency different from that of any multiple supplied by either of the harmonic generators.

This will be further considered in connection with the drawings, in which Figs. 1 and 2 show a wireless sending and receiving station respectively, in which control oscillations supplied at the sending station are employed to maintain a constant phase and frequency relation between the carrier oscillations and the reinforcing oscillations. Figs. 3 and 4 show diagrammatically a sending and receiving station respectively of a multiplex system, in which the carrier and reinforcing

5 frequencies used are multiples of the control frequency. Figs. 5 and 6 show a sending and receiving station respectively of a multiplex system, in which the number of carrier frequencies is increased by combining the multiple frequencies from two harmonic generators, and frequencies are obtained which are not multiples of each other.

10 Referring to Fig. 1, the oscillation generator O, of the general type disclosed and claimed in the patent to Hartley, oscillation generators, 1,356,763 patented October 26, 1920, supplies control oscillations and comprises a three-element vacuum tube of the audion type, in which the input circuit is inductively connected to the output circuit by means of the coils 2 and 3. The space current in this tube is supplied by the battery 4. By means of the variable condenser 5, shunted across the coils 2 and 3, the frequency supplied by the generator may be given any desired value. This oscillation generator which supplies control oscillations is connected to the input circuit of the amplifier A of the audion type. The grid 6 of this amplifier is supplied with negative potential by means of battery 7. The space current in the output circuit of the amplifier is supplied by the battery 8 through the impedance 9. The filaments 10 and 11 of the oscillation generator and amplifier are heated by the common battery 12. Amplified oscillations in the output circuit of the amplifier A are supplied by means of the transformer T 25 to the input circuit of the harmonic generator G, which is a three-element vacuum tube of the audion type.

40 The harmonic generator G is described and claimed in the application of Kendall, for generator and generation of multiple frequencies, Serial No. 139,530, filed December 29, 1916, Patent No. 1,446,752, granted February 27, 1923, and as noted therein the harmonic generator is overloaded so as to 45 produce a maximum distortion of the wave form supplied by the harmonic generator. Since a distorted wave may be considered as composed of a pure sine wave of the same frequency as the distorted wave, and a plurality of harmonics having higher frequencies, it remains to select the particular higher frequency which it is desired to transmit.

55 The filament 13 of the harmonic generator is heated by the battery 14 and the space current in the output circuit is supplied by the battery 15 through the impedance 16. The condenser 17, in shunt to the impedance 16 and battery 15, provides a path for the high frequency currents. The harmonic generator is coupled by means of the transformer T₁ to an amplifier A₁ which is similar to amplifier A above described. The output circuit of amplifier A₁ is tuned by means of the condenser 18 to the particular harmonic fre-

quency oscillations to be selected from the complex wave in the output circuit of the harmonic generator and supplied as a carrier wave. Amplifier A₁ is coupled by means of transformer T₂ to another amplifier A₂, both input and output circuits of which are tuned by means of the condensers 19 and 20 respectively to the harmonic frequency selected from the harmonic generator. The selected carrier oscillations are transferred by means of the transformers T₃ and T₄ to the input circuit 21 of the modulator M.

70 This modulator M is described and claimed in the patent to Hendrick J. Van der Bijl, 1,350,752, patented August 24, 1920. This 75 modulator comprises a three-element vacuum tube 22 of the audion type, the grid 23 of which is maintained at a negative potential by means of the battery 24. The output circuit of tube 22 comprises condenser 25, which 80 shunts the impedance 26 and the source 27. This output circuit is tuned to the frequency to be transmitted by means of the condenser 28. The modulator M is coupled to antenna 29 by means of the transformer T₅.

85 By means of the line 30, amplified control oscillations of the frequency generated by the oscillator O are supplied to the filter F, which selectively transmits oscillations of the control frequency to the transformer T₆, 90 coupled to the input circuit of the modulator M. The signal to be transmitted is transferred from the line L to the input circuit of the modulator M by means of the transformer T₇.

95 The carrier oscillations supplied by the transformer T₄ are then modulated in accordance with both the control oscillations supplied by the transformer T₆ and the signal currents in line L. The carrier oscillations, as modulated, are then transmitted from the antenna 29 and received by the antenna 50, shown in Fig. 2. The antenna 50 is coupled by means of transformer T₈ to the amplifier A₂, the input circuit of which is tuned to the frequency of the oscillations to be received by means of the condenser 31. The amplifier A₂ is similar to the amplifiers above described and is essentially unilaterally conducting for a purpose that will be later described. The output circuit of amplifier A₂ is coupled to the detector D, the input circuit of which is suitably tuned by means of the condenser 32. This detector is a vacuum tube of the well-known audion type. The output circuit of the detector D is coupled by means of the transformer T₉ to the filter F₁, which selectively transmits detected control oscillations of the frequency generated by the oscillator O.

100 By means of the transformer T₁₀, the output circuit of detector D is also coupled to the filter F₂, which suppresses all frequencies above 2500 cycles and which transmits exclusively the detected audible signaling currents.

The filter F_1 selectively transmits the control oscillations to the power limiting tube and harmonic generator G_1 , which comprises a three-element vacuum tube of the audion type. The potential of the grid 33 of the device G_1 is maintained positive by means of the battery 34. The positive grid attracts the electrons emitted by the filament 35, and when the potential supplied to the device G_1 reaches a sufficiently high positive value, the electrons will be attracted to the grid to such an extent that no further increase in the current in the plate circuit occurs. The minimum value of the space current in G_1 being zero, it is evident that the power delivered by this tube is limited; and such limitation is necessary in order to prevent singing in the circuit comprising the elements T_9 , F_1 , G_1 , Δ_4 , A_5 and T_{10} , which serve to couple the output circuit of detector D to its input circuit. Any other form of power limiting device may however be used.

The device G_1 operates as a harmonic generator by reason of the fact that it is over-loaded as noted above. Carrier frequency reinforcing oscillations from the harmonic generator G_1 are supplied to the amplifier A_4 , the input circuit of which is tuned by the variable condenser 36. The phase of the amplified reinforcing oscillations is properly adjusted by means of the variable inductance 37, variable capacity 38 and variable resistance 39. Amplified reinforcing oscillations of the proper phase are supplied to the resistance 40, which serves as a source of potential for the input circuit of the amplifier A_5 , the output circuit of which is coupled to the input circuit of detector D by means of the transformer T_{10} . Oscillations from transformer T_{10} cannot, however, be transmitted through amplifier A_3 to antenna 50, since amplifier A_3 is asymmetrically conducting and only permits the passage of currents in the direction from the antenna to the detector D .

It will be apparent then that control oscillations supplied by the oscillator O and the signal currents sent over the line L will serve to modulate the carrier oscillations supplied by the transformer T_4 from the harmonic generator G . The modulated oscillations are transmitted from antenna 29 and are received by the antenna 50. The detector D supplies detected control oscillations which are selectively transmitted by means of the filter F_1 to the harmonic generator and power limiting tube G_1 . The device G_1 , operating as a harmonic generator, supplies reinforcing oscillations of the carrier frequency and these oscillations are amplified by the amplifier A_4 . The phase of the reinforcing oscillations is properly adjusted by means of the variable inductance 37, variable capacity 38 and variable resistance 39. Reinforcing oscillations having a proper phase with relation to

the carrier oscillations are then amplified by the amplifier A_5 and transferred to the input circuit of the detector D , where the reinforcing oscillations combine with the received modulated oscillations, thereby intensifying both the received control oscillations and the low frequency signal up to an amount which is limited by the capacity of the power limiting device G_1 to pass control oscillations from filter F_1 to amplifier A_4 . The object of this intensification is to reproduce in line L_1 the signal which originated in the line L . The signal currents are then supplied by means of the transformer T_{11} to the line L_1 , the filter F_2 serving to suppress all the frequencies above the audible range.

Since the carrier oscillations and the reinforcing oscillations are derived from a common source, and since both are provided by changing the frequency of the oscillations supplied by that source, it follows that the carrier frequency and the reinforcing frequency will always be identical; which is essential for the proper reception of the telephonic signal. It is to be noted here that the selecting devices, i. e., tuned circuits and filters employed, will properly differentiate between the various frequencies involved, even though the control frequency and its multiple are subject to small variations.

The oscillation generators, amplifiers and harmonic generators shown in the remaining figures are similar to those described above. Referring to Fig. 3, there is shown a multiplex sending system in which the harmonic generator supplies a plurality of carrier frequencies, each of which may be modulated with a signal to be transmitted. The control oscillations supplied by the oscillation generator G_1 are amplified by means of the amplifier A_{25} , and amplified control oscillations are supplied by means of the transformer T_{31} to the input circuit of the harmonic generator G_2 .

The several carrier oscillations supplied by the generator G_2 are amplified by means of amplifier A_6 , the output circuit of which comprises the two tuned circuits 40 and 41, each of which is tuned to a different harmonic supplied by the harmonic generator G_2 . Carrier oscillations supplied by the tuned circuit 40 are amplified by means of the amplifier A_7 from which amplified carrier oscillations are selectively transmitted by means of the filter F_3 to the modulator M_1 . Similarly, the tuned circuit 41 supplies amplified carrier oscillations of a frequency different from that supplied by the tuned circuit 40, to the amplifier A_8 , which is coupled to the filter F_4 , which selectively transmits carrier oscillations to the modulator M_2 .

The modulator M_1 comprises two three-element vacuum tubes of the audion type, 42 and 43, which have their input circuits connected in opposition. The signaling currents are supplied to the modulator M_1 by

means of the line L_2 . The transformer T_{12} has two coils serially connected in its secondary circuit, and the transformer T_{13} supplies carrier oscillations between the 5 points of division of the divided input circuits of the tubes 42 and 43. This modulator is described and claimed in patent to Carson, 1,343,306 patented June 15, 1920, "Duplex translating circuits". The output circuit of 10 the modulator M_1 is coupled by means of the transformer T_{14} to the filter F_5 , which suppresses any low frequency signals that might otherwise be transmitted to the high frequency line L_3 . The modulator M_2 is 15 provided with the low frequency line L_4 , and this modulator is coupled through the filter F_6 to the high frequency line L_3 .

By means of the coil 62 of the transformer T_{21} , some of the control oscillations are supplied to the filter F_7 , which selectively transmits only oscillations of the control frequency to the line L_5 in circuit with the high frequency line L_3 . The modulators M_1 and M_2 serve to suppress the unmodulated component of the carrier wave and each transmits a pure modulated wave to the line L_3 , which is also supplied with control oscillations from the line L_5 .

The oscillations transmitted to the high frequency line L_3 are received by the receiving station shown in Fig. 4. The filter F_8 , connected to the line L_3 , supplies control oscillations to the amplifier A_9 , coupled to the harmonic generator G_4 , which supplies reinforcing oscillations of the various carrier frequencies to the amplifier A_{26} similar to the amplifier A_6 , shown at the sending station in Fig. 3.

In Fig. 4, the tuned circuits 60 and 61 supply amplified reinforcing oscillations of the carrier frequencies to the amplifiers A_{10} and A_{11} , respectively. Amplified reinforcing oscillations are supplied by means of the transformers T_{15} and T_{16} to the input circuit of detector D_1 . The resistance 44, connected across the line L_3 , serves as a source of modulated oscillations for the unilateral amplifier A_{12} , which prevents the oscillations supplied by transformer T_{16} from being transmitted to the line L_3 . The amplifier A_{12} supplies amplified modulated oscillations to the resistance 45, which serves as a source of potential for the detector D_1 . The reinforcing oscillations supplied by 55 transformer T_{16} are combined with the received modulated oscillations to reproduce in the output circuit of the detector D_1 the low frequency signal, which originally effected the modulation of the carrier oscillations at the sending station shown in Fig. 3. The output circuit of the detector D_1 is coupled to the filter F_9 , which suppresses all frequencies above the audible range.

The circuits associated with the output 60 circuit of amplifier A_{11} are similar to those

just described in connection with amplifier A_{10} .

The filter F_8 will separate out the control oscillations from the other transmissions and the tuned circuits will also isolate the proper multiples of the control frequency even though this frequency varies by small amounts. As both the carrier oscillations at the sending end and the reinforcing oscillations are here derived as multiples of the same control oscillations, it is evident that they will have identical frequencies.

In the system shown in Figs. 1 and 2, the control oscillations were transmitted as modulated oscillations of the carrier wave, while in Figs. 3 and 4, the control oscillations are directly transmitted over the high frequency line L_3 .

The system shown in Fig. 5 is similar to that in Fig. 3, with the addition of means whereby carrier frequencies are provided which are not multiples of the control frequencies used and this serves to increase the number of carrier frequencies within a given range. The oscillation generator O_2 , shown in Fig. 5, will be considered as supplying control oscillations of a frequency equal to 3000 cycles, which are amplified by means of amplifier A_{13} , and transmitted by transformer T_{20} to the harmonic generator G_4 . Amplified carrier frequencies are supplied from the harmonic generator G_4 to the amplifier A_{14} , the output circuit of which contains the tuned circuits 46, 47 and 48. The circuits 47 and 48, by way of example, may be tuned to a frequency of 9000 cycles while the circuit 46 may be tuned to some other frequency, such as 12,000. It is, of course, obvious that any number of other tuned circuits may be provided in the output circuit of the amplifier A_{14} to provide sources of as many different carrier oscillations as desired. By means of the tuned circuit 47, carrier oscillations of frequency 9000 are supplied to the filter F_{11} , which selectively transmits the carrier frequency 9000 to a modulator M_3 similar to the modulators M_1 and M_2 already described. By means of the tuned circuit 48, amplified oscillations of frequency 9000 are transferred 115 to the input circuit of the combiner C .

It is shown in the application of Kendall, Serial No. 121,571, filed September 22, 1916, Patent No. 1,734,132, granted November 5, 1929, that if oscillations of two different frequencies are supplied to the input circuit of a device having a curved voltage-input current-output characteristic that there will appear in the output circuit frequencies equal to the sum and difference of frequencies supplied to this device. As noted in the said application, No. 121,571, of Kendall, a vacuum tube of the audion type has a curved characteristic, and the combiner C is such a tube.

The oscillator O_3 may be considered as generating control oscillations of frequency 4000 cycles which are amplified by the amplifier A_{15} and transmitted by the transformer T_{21} to the harmonic generator G_5 . The details of the last named elements have not been shown in the drawings as they are similar to the sending circuit associated with the oscillator O_2 . The harmonic generator G_5 may supply carrier oscillations of frequency 16,000 to the amplifier A_{16} . Amplified carrier oscillations of frequency 16,000 are supplied from the amplifier A_{16} through the filter F_{13} to the modulator M_4 . Amplified oscillations of frequency 16,000 are transferred by means of the transformer T_{16} to the input circuit of the combiner C , and amplified oscillations of frequency 9000 are transferred by means of the transformer T_{17} to the input circuit of this combiner. The output circuit of the combiner C then becomes a source of carrier oscillations of a frequency 25,000, which are selectively transmitted through the filter F_{14} to the modulator M_5 . Low frequencies sent over the lines L_7 , L_8 and L_9 , associated with the modulators M_4 , M_5 and M_3 respectively, effect a modulation of the carrier oscillations supplied to these modulators. The output circuits of the modulators M_4 , M_5 and M_3 supply modulated carrier oscillations through the filters F_{15} , F_{16} and F_{17} respectively to the high frequency line L_{10} . By means of the third winding 65 on the transformer T_{20} , control oscillations generated by oscillator O_2 are transferred to filter F_{10} which selectively transmits oscillations of 3000 cycles to the line L_{10} . Similarly, transformer T_{21} transmits control oscillations generated by oscillator O_3 to filter F_{12} and thence to line L_{10} . Each of these filters prevents the control oscillations transmitted to the line L_{10} from the other filters from interfering with the carrier oscillations supplied by its associated generator. Line L_{10} is then adapted to transmit control oscillations of frequency 3000 and 4000, and also modulated oscillations having the carrier frequencies 9000, 16,000 and 25,000.

The number of control current generators shown in the drawings is only two, but it is obvious that any number of these may be used, and it is also obvious that other combiners may be used in order to produce various other frequencies which are not multiples of the frequencies supplied to this combiner.

The line L_{10} in Fig. 5 is terminated in the resistance 53, shown in Fig. 6, which serves as a source of oscillations for the various circuits in shunt to this resistance. In shunt to resistance 53 is the amplifier A_{17} , the output circuit of which is connected to the filter F_{18} which transmits control oscillations of a frequency of 3000 cycles. Control oscillations of this frequency are supplied from the filter F_{18} to the harmonic generator G_6 , coupled to the amplifier A_{18} , the output circuit of which contains the tuned circuits 54, 55 and 56. The circuit 54 is tuned to the same frequency as the circuit 46 in Fig. 5. The circuit 55 is tuned to the frequency 9000 and is coupled to the filter F_{19} , which serves to selectively transmit reinforcing oscillations of the carrier frequency 9000 to the input circuit of the detector D_2 . The circuit 56 is tuned to a frequency of 9000, and currents of this frequency are supplied to the input circuit of the combiner C_1 .

The amplifier A_{19} , filter F_{20} and harmonic generator G_7 are similar to the corresponding elements A_{17} , F_{18} , G_6 described above, the difference being in the adjustment of these elements whereby filter F_{20} selectively transmits control oscillations of a frequency of 4000 cycles to the harmonic generator G_7 which supplies reinforcing oscillations of frequency 16,000 to the amplifier A_{20} . The output circuit of amplifier A_{20} comprises the circuits 57 and 58 which are tuned to the reinforcing frequency 16,000, which is the same as one of the carrier frequencies. Oscillations of frequency 9000, supplied to the combiner C_1 by means of the tuned circuit 56, and oscillations of frequency 16,000, supplied to this combiner by means of the tuned circuit 57, produce in the output circuit of this combiner oscillations of the reinforcing frequency 25,000, which are selectively transmitted through the filter F_{21} to the detector D_3 . Also oscillations of frequency 16,000 are supplied from the tuned circuit 58 through filter F_{22} to the input circuit of the detector D_4 .

Amplifier A_{21} is connected in shunt to the resistance 53, and amplified modulated oscillations are supplied by this amplifier to detector D_4 . The amplifier A_{21} is essentially unilaterally conducting in order that the reinforcing oscillations, supplied to the input circuit of detector D_4 , may not be transmitted through the amplifier A_{21} to the high frequency line L_{10} . The modulated oscillations supplied to the detector D_4 by the amplifier A_{21} and the reinforcing oscillations supplied by the tuned circuit 58 combine to reproduce in the output circuit of the detector D_4 the signal which originally effected the modulation of the carrier oscillations of frequency 16,000. The filter F_{21} suppresses all frequencies above 2500 and transmits audible frequencies to the line L_{15} .

The connections of the detectors D_2 and D_3 to the high frequency line L_{10} are similar to the circuits associated with D_4 which have been described.

The low frequency signaling lines at the transmitting and receiving stations are shown supplied with telephone transmitting and receiving apparatus. Obviously, this system is not limited to telephonic signaling, but may be equally well applied to telegraph or

other signaling or, in fact, to selective transmission of any kind.

What is claimed is:

1. The method comprising modulating a carrier wave in accordance with control energy, transmitting and detecting said wave to reproduce said control energy at a receiving station, and utilizing said detected control energy to reinforce said transmitted carrier wave.
2. The method of transmission comprising modulating a carrier wave in accordance with control energy, transmitting said modulated wave and detecting it at a receiving station to reproduce said control energy, amplifying said control energy and utilizing said amplified control energy to reinforce said transmitted carrier wave.
3. The method comprising modulating a carrier wave in accordance with control energy, transmitting and detecting said wave to reproduce said control energy at a receiving station, and deriving from said detected control energy a reinforcing wave of the frequency of said carrier wave.
4. The method which comprises generating a wave of low frequency, obtaining a wave of a single higher frequency from said wave of low frequency, freeing the wave so obtained from waves of other than said single frequency and modifying said wave of higher frequency in accordance with said wave of low frequency.
5. The method which comprises modulating a carrier wave by both signals and a control wave, transmitting said modulated wave to a receiving station, detecting said received wave to obtain the control wave component, and producing from said component reinforcing oscillations of said carrier wave frequency.
6. The method of signaling which comprises modulating a carrier wave in accordance with both signals and control energy, transmitting said modulated wave, receiving and detecting said wave, producing reinforcing oscillations from the control energy component of said wave, and combining said reinforcing oscillations with said received wave.
7. The method of carrier wave transmission which comprises modulating a carrier wave in accordance with control oscillations, transmitting said modulated wave to a distant station and there detecting it to obtain control oscillations, producing locally generated oscillations at said receiving station for combination with said received carrier oscillations, and causing said control oscillations to control the frequency difference of said carrier and said locally generated oscillations.
8. The method of telephony comprising simultaneously transmitting speech current energy and control energy as modulations of

the same carrier wave, receiving said transmitted energy, causing said received control energy to produce reinforcing oscillations, and utilizing said reinforcing oscillations to reinforce said speech current energy.

9. The combination with means for generating a wave of low frequency, of means for obtaining therefrom a wave of higher frequency, means for freeing the higher frequency wave so obtained from waves of other than its single frequency and means for modifying said wave of higher frequency in accordance with said wave of low frequency.

10. The method of homodyne transmission which comprises modulating a carrier wave in accordance with control energy, transmitting said wave and detecting it at a receiving station to reproduce said control energy, deriving from said reproduced control energy reinforcing oscillations of the frequency of said carrier wave, and regulating the phase of said reinforcing oscillations with respect to that of said transmitted carrier wave.

11. The method of reinforcing a received modulated carrier wave which comprises detecting said wave, deriving from a detected component thereof reinforcing oscillations of the frequency of said carrier wave, and combining said oscillations with said received wave.

12. The method of reinforcing a received modulated carrier wave which comprises detecting said wave, deriving from a detected component thereof reinforcing oscillations of the frequency of said wave, and combining said oscillations with said received wave after limiting the magnitude of said oscillations in order to prevent generation of continuous oscillations.

13. A multiplex transmission system comprising means for transmitting control oscillation energy, means for receiving said transmitted control oscillation energy, means for deriving from said received energy harmonic frequency oscillations, and means for amplifying said harmonic frequency oscillations to substantially the same magnitude.

14. A transmission system comprising means for transmitting simultaneously, modified carrier oscillations and control energy, means for receiving said oscillations and said energy, means for causing said received control energy to produce reinforcing oscillations of said carrier frequency, and means for adjusting the phase of said reinforcing oscillations with respect to that of said received carrier oscillations.

15. A transmission system comprising means for producing a carrier wave and modulating said wave in accordance with signals, means for transmitting and means for receiving said modulated wave, means for detecting said received carrier wave to reproduce said signals, means including a frequency selective circuit for supplying rein-

forcing oscillations of the carrier frequency to said detecting means, and additional means for adjusting the phase of said reinforcing oscillations.

5 16. A transmission system comprising means for producing a carrier wave and modulating said wave in accordance with both signals and control energy, means for transmitting and means for receiving said modulated wave, means for detecting said received carrier wave to reproduce said signals and said control energy, means for deriving from said detected control energy reinforcing oscillations of said carrier frequency, and means for adjusting the phase of said reinforcing oscillations with respect to that of said received carrier wave.

10 17. A signaling system comprising a detector, means for supplying a modulated wave of a given carrier frequency thereto, means for deriving reinforcing oscillations of said carrier frequency from said detected wave and for impressing said oscillations upon said detector simultaneously with said wave, and means for preventing continuous transfer of energy from said detector back to itself.

15 18. A signaling system comprising a detector, means supplying to said detector carrier oscillations modulated in accordance with control energy, means for detecting said control energy and deriving therefrom reinforcing oscillations of said carrier frequency, and means for applying said reinforcing oscillations to said detector, said several means comprising a power-limiting device to prevent continuous transfer of energy from said detector back to itself.

20 19. The method of signaling comprising transmitting signals and control waves as components of a complex wave, utilizing at a receiving point the control wave component to control a locally derived wave and reproducing the signal by cooperation of the locally derived wave with the signal component of the complex wave.

25 20. In a system of signaling in which wave energy is produced and is added at a receiving point to the wave received from the transmitting point, the method of signal reception comprising utilizing a component of the received wave to control the frequency of the wave so added at a receiving point.

30 21. The method of synchronizing the operation of apparatus at a certain relatively low frequency when the apparatus is located at two places far apart, which consists in generating at one place an electric current of a higher frequency definitely related to said first mentioned frequency, and transmitting such higher frequency current to the other place and applying it to determine the operation of the apparatus there at said first mentioned frequency.

35 22. The method of synchronizing appara-

tus to a certain relatively low frequency at two places, which consists in transmitting a current of harmonic frequency from the apparatus at one place and applying it to effect synchronization at the said relatively low frequency at the other place.

40 23. The method of synchronizing apparatus to a certain relatively low frequency at two places, which consists in generating at one place a current of higher frequency and definitely related in phase and frequency to the said current of relatively low frequency and transmitting said higher frequency current and applying it at the other place to effect synchronization at the said relatively low frequency.

45 24. In combination, a transmission medium incapable of transmitting currents of relatively low frequency, apparatus at two places to be synchronized at a relatively low frequency, and means for generating a harmonic current at one of those places and transmitting it over said medium and applying it at the other place to synchronize the apparatus thereat with the apparatus where the said harmonic current was generated.

50 25. In a transmission system, a band filter for transmitting currents of only a limited range of frequencies, a circuit for supplying current to said band filter, a source of current of single frequency outside the range of said filter connected to said circuit, and modulating means in said circuit whereby the frequency of the current from said source is changed to a frequency within the range of said band filter.

55 26. In a signaling system, means for generating a sustained alternating current, means for continuously modulating said alternating current according to message signals, means for receiving said modulated current, means for dividing said received current into message signal currents and into synchronizing signal currents, and means synchronized by said synchronizing signal currents.

60 27. In a signaling system, means for generating a sustained alternating current, means for continuously modulating said alternating current according to message signals, means for receiving said modulated current to produce message signals, and means synchronized by utilizing a portion of said received current.

65 28. In a signaling system, means for generating a sustained alternating current, means for continuously modulating said alternating current according to message signals, means for receiving said modulated current, means to be synchronized and means for utilizing said received current both for reproducing the signals and for synchronizing.

70 29. In a signaling system, means for generating a sustained alternating current.

means for continuously modulating said alternating current according to message signals, means for receiving said modulated current to produce message signals, synchronizing means, and means for utilizing energy derived from said received current for controlling said synchronizing means.

30. The method of receiving a signal modified high frequency wave which comprises utilizing a portion of the energy of said wave to synchronize a local device for producing waves and combining other energy of said wave with wave energy from said source.

31. The method of signaling which consists in transmitting a composite wave-train including a signal-modulated component and a synchronizing component, deriving from the synchronizing component at the receiving station a local wave-train separate from but synchronous with the received signal-modulated component, amplifying said synchronous local wave-train separately from the received signal-modulated component, and combining the amplified synchronous local wave-train with the received signal-modulated component to produce a signal-conveying effect.

32. A signaling system comprising means for generating a carrier current, means for modulating said current at the same time both in accordance with signals and control impulses, means for receiving said modulated current, means for detecting, means to be synchronized, and means for utilizing the detected control impulses for synchronizing.

In witness whereof, I hereunto subscribe my name this 19th day of October, 1928.

BURTON W. KENDALL.
